UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-LINING.

SPECIFICATION forming part of Design No. 36,055, dated September 9, 1902.

Application filed July 29, 1902. Serial No. 117,575. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Linings, of which the following is a full, clear, and exact description, reference being had to the accompanying drawing, forming part hereof, in which the invention is represented in front view.

The leading features of the design consist in the representations in relief of two nude boy figures at work in a blacksmith's forge, one figure at the forge-fire with one hand uplifted grasping the bellows-rope and the other hand holding an article extended into the fire, while the other figure is at the anvil with one hand holding the work on the anvil and the

other uplifted, grasping a hammer. The lining shows in its upper portion the representation of one side of the forge-room having a small window therein and the plastering scaled off in spots, displaying the brickwork. The lower part of the lining represents the forge-floor composed of stone slabs of irregular shapes, with sundry articles standing around thereon.

I claim—

The ornamental design for a fireplace-lining as herein shown and described.

In testimony whereof I have hereunto set my hand in the presence of two subscribing witnesses.

THOMAS M. DUDGEON.
